UNITED STATES PATENT OFFICE.

JOHN BRAUER, OF MENASHA, WISCONSIN.

SHIPPING-CASE-COVER FASTENER.

No. 897,343.

Specification of Letters Patent.

Patented Sept. 1, 1908.

Application filed March 11, 1908. Serial No. 420,323.

To all whom it may concern:

Be it known that I, JOHN BRAUER, a citizen of the United States, residing at Menasha, in the county of Winnebago and State of Wisconsin, have invented a new and useful 5 Shipping-Case-Cover Fastener, of which the following is a specification.

My invention relates to a wire shipping case cover fastener, and is particularly adapted for use upon pails formed of wood turned into a round form for packing cases, such as pails in which tobacco, candy, and confectionery of various kinds are shipped from the wholesaler to the retailer, but is applicable 10 also to pails made of veneer and fiber, and also to rectangular boxes formed of wood which it may be desired to use for shipping packages, and the objects of my invention are, first, to provide a fastening device for such use, and 15 second, one that is easy to make and apply; second, one that is of low cost; third, in the case of pails, one that can be applied to them before they are packed one within the other in packages of a dozen at the manufactory where 20 made, and from whence they are shipped to the wholesaler of such ware for distribution to the wholesale grocers who use them for shipping cases; fourth, one that is adapted for use with covers formed of hard woods, 25 such as maple, birch, &c, by reason of the lessened difficulty in using such covers which have heretofore been secured to the pail by nailing; fifth, one that can be applied in such 30 a manner that it cannot be removed, without 35 the fastening device indicating by its mutilation, the probability of the contents of the package having been tampered with while in transit between the packer and shipper of the goods and the consignee, so that if any loss 40 takes place in transit, it will be apparent to the receiver and can be at once and correctly 45 located.

The present invention is an improvement on one for a like purpose for which Letters Patent of the United States were filed in the 45 Patent Office November 25, 1907, Serial No. 403,614, and it is shown in the accompanying drawing, in which,

Figure 1 is an elevation in perspective of a 50 pail having a cover, with my improved fastening device applied to the pail and its cover, the device upon the top of the cover being identical with one modification of a fastening shown in the application above referred to. 55 Fig. 2 is an elevation in perspective of a pail without a cover, and showing the manner of

securing the wire of the fastener to a shipping case, and also, the manner of disposing of said wire in packing pails one within the other into dozen (more or less) packages for 60 shipment from the manufactory where the pails are made. Fig. 3 is a plan showing the wire of the fastener bent at each end into a hook form as it is for securing the ends to a pail, the wire being inserted into the staves of 65 a pail through bores therein, the staves being in section across said bores.

Similar numerals indicate like parts in the several views.

1, indicates a pail; 2, wire hoops thereon; 70 3, its bail; 4, its bail ears; 5, a series of small bores through the pail near its top, eight in number. These holes are to be arranged in pairs, two pairs for each wire, the pairs may be spaced around the pail at 75 nearly equal distances, but those of each pair need be but a fraction of an inch apart. These bores are to receive the ends 6 and main body of the wire, 7 of the wire 8. For the fasteners I prefer to use about No. 15 80 soft wire for ordinary candy and tobacco pails which is cut into suitable lengths and one end may have the right angled bends 9 and 10 made upon it and forming a hook, before the wire is inserted into the bores 5, 85 said bends upon the other end not being made until after the insertion of the wire from the inside of the pail through one hole of a pair, the wire then being bent around the outside of the pail and its free end inserted through one of an adjoining pair of 90 holes, when the bends 9 and 10 are to be made in that end of the wire. The wire is then to be pulled by its slack 11, and the ends 6 inserted into the other one of said pairs of 95 holes, the wire between the bends 9 and 10 being struck with a hammer as the wire is pulled and embedded into the body of the staves 12 of the pail, flush with their inner surface. The wire is then to be pulled up 100 tightly by its slack and bent over the top edge of the pail, as is shown on the front side of the pail in Fig. 2, and then bent downward into the pail as is shown upon the rear inside of the pail in said figure. The 105 two wires 8 being inserted and the portion between the bends 9 and 10 being embedded in the wall of the pail, the slack being bent down upon the inside of the pail, the pails are in a condition for packing one within 110 the other with the fastening wires inside of them ready for use and in no way interfering

with their being packed. It may be noted that the hooks formed by the bends 9 and 10, may be outside instead of inside of the semicircle of wire, and not depart from the intent of the invention. The pail covers 13, are usually tied or racked up in one dozen lots for shipment with the pails. After the arrival of the pails and covers at the place of use, they are to be unpacked and the slack 11 of the wire bent outward over the pail top, when the pails can be filled with the goods desired up even with the pail top. The cover being then placed in position, the slack 11 of the two wires of the fastener are brought together and twisted around each other by means of a special tool in the opening 14 of the twist 15 in Fig. 1, until the wires are tightened over the cover to the necessary degree.

20 For opening the packet, the same special tool may be used in the opening 14 and the wires untwisted, or they may be cut with a pair of tinner's snips, but they cannot be again twisted together over the cover without their mutilation in so doing being observable.

It may be observed that the bores 5 are substantially of the same diameter as that of the wires, so that no difference in their size is apparent, and they being so near the top of the pail they do not detract from its value as a pail for later uses, and the bores being even but the minor fraction of an inch apart for the pairs, no amount of strain 35 likely to be given the fasteners will separate them from the pail.

Having described my invention, what I claim and desire to secure by Letters Patent, is, —

40 1. In a fastener for a pail or other shipping case cover, comprising two wires, each of

which wires extends from the inner to the outer side of said shipping case near its upper edge and forms an outer loop in the slack of each wire, which two loops are bent upward 45 over the cover and toward its center where they are twisted together, four bores through said shipping case wall near its upper edge for each of said two wires, arranged in pairs spaced apart, each end of the wire of each of 50 said loops passing from the outer to the inner side of said case through one bore of each pair, thence being bent at a nearly right angle toward the other bore of the pair, thence at a nearly right angle and entering 55 the other bore of said pair, the wire between said two bends upon each end of the wires being driven into the wall of the shipping case, flush with its inner surface.

2. As a member of a pail or other shipping case cover fastener, a wire bent into a nearly semicircular form, a hook formed upon each end of the wire, the free end of each hook being spaced apart from the main body of the wire and arranged in a position 60 parallel with said main body, the main body being adapted to pass from the outer to the inner side of said case through one of a pair of bores therein, and the free end aforesaid being adapted to enter from the inside 65 of the case, the second bore of the pair.

3. A wire shipping case cover fastener, a hook upon an end of the wire for preventing it from being pulled through the wall of the case, the wire of which hook incloses three 70 sides of a rectangular space having two slightly rounded corners.

JOHN BRAUER.
